APPARATUS FOR MOUNTING TILE

August Staudt, Perth Amboy, N. J.

Application June 24, 1933. Serial No. 677,374

6 Claims. (Cl. 41—1)

This invention is an apparatus for mounting tile. It has long been the practice in the mounting of tile to assemble tiles of appropriate shape and colors in predetermined designs or relation upon sheets of paper through the use of a suitable adhesive. The tiles are secured in predetermined relation with their finished faces in contact with a piece of paper of convenient size and in slightly spaced apart relation with respect to one another. The paper with tiles attached are furnished in this condition to the tile setter or mason who installs them in the following manner.

A suitable foundation or backing is provided at the place of installation. Over this foundation is flowed or troweled a layer of cement or mortar of appropriate thickness and consistency. This is leveled off and thereupon the papers with tiles thereon are applied to the cement by laying the tiles back down in the cement and pressing them firmly in place. A sufficient number of paper and tile assemblies are positioned edge to edge in cement to cover the desired space to be tiled. During the pressing of the tiles in place the cement or mortar which is of appropriate thickness or consistency works up between the tiles and forms a proper seating or bed therefor.

After the cement has set, the paper backing is moistened and scrubbed or scraped off leaving the finished faces of the tile in exposed position. A thin grout is then flowed over the tiles to fill the voids between them to produce a flush finished surface. The tiles are thereupon washed and thoroughly cleaned to produce the finished work.

In order that the finished designs produced in the manner described may be obtained, there is used in the assembling of the tiles "mounting boards." These mounting boards are made in the form of a substantially flat slab, the upper surface of which is provided with pockets to receive the tiles.

Under prior practice, when it is desired to make, for example, a two color design, this is accomplished by first filling all of the space of the board with tiles of the first color and is generally accomplished by dumping tiles upon the board and shaking the board until the tiles are seated in practically all of the spaces. The operator thereupon scrapes off excess tiles which have not seated in any space and laboriously picks out tiles from the spaces appropriate to the other color of the desired design. This picking out of tiles is accomplished by hand, is a laborious task and injurious to the hands of the

operator. Even when carried out by the most skilled operators, there is the human element of error and it is not uncommon to find that in the more complicated patterns that improper tiles have been picked out and that errors occur in the finished design. Nevertheless the practice has been to pick these tiles out manually and after they have been picked out, a quantity of tiles of the other color are deposited on the board and the board is shaken to fill the spaces which have been previously manually emptied. After these spaces have been filled so that all the spaces in the board are now filled. Excess tiles are now scraped off and the board may thereupon be advanced to the next operation of applying the paper backing adhesively to the tiles to prepare them for the market.

The foregoing operations have been practised in the tile industry from time immemorial. The majority of the work is carried out by manual labor which is not of a skilled character and which cannot be depended upon for accurate results.

With the foregoing considerations in mind, the object of the present invention is to provide a simple, though highly efficient, apparatus for facilitating the preparation of boards for designs of different colors, and this invention provides a thoroughly efficient and economical apparatus for accomplishing this result.

The apparatus of this invention embodies, generally speaking, an appropriate electromagnet, a plurality of boards, such as are commonly used in the art, and an appropriate number of filler members of appropriate design and materials as hereinafter described, and suitable means for supporting the board and moving it into and out of cooperative relation with the electromagnet.

An important feature of the present invention is inherent in the fact that I may employ conventional mounting boards as heretofore used without requiring any change in the structure of these boards and without employment of complicated mechanism in carrying out the present invention. The structure is extremely simple and at the same time highly efficient in the carrying out of its intended functions.

Features of the invention, other than those adverted to, will be apparent from the hereinafter detailed description and claims, when read in conjunction with the accompanying drawing.

The accompanying drawing illustrates one practical embodiment of the invention, but the construction therein shown is to be understood as

illustrative only, and not as defining the limits of the invention.

Figure 1 is a perspective view of apparatus embodying the present invention.

5 Figure 2 is a fragmental perspective view of a conventional mounting board.

Figures 3, 4 and 5 are perspective views showing illustrative forms of filler pieces which I may employ according to this invention.

10 Figures 6, 7, 8, 9 and 10 are diagrammatic views showing different steps in the operation of the method.

15 Referring to the drawing, 1 designates a suitable table which, in practice may, if desired, be the conventional table generally found in tile works and employed in the mounting of tiles by hand under present practice.

20 Positioned upon said table is a supporting bed 2 provided along two of its margins with limiting guides or stops 3 and 4, so that when a mounting board of a conventional kind is positioned upon said table, it may be moved into contact with both stops, so as to position it accurately upon the bed 2.

25 Positioned above the bed in vertical spaced relation thereto is an electromagnetic element 5, which may be of any approved form. The function of this element is to operate as an electromagnet and it should be of such type that it may be electrically energized and when the current is shut off, it will rapidly de-energize and not retain appreciable residual magnetism. Electromagnetic elements of this kind are well known in the various arts and it is not considered necessary to show the same in detail. It may be noted, however, that the electromagnetic element is included in a suitable energizing circuit 6 including therein a visual signal 7 and a controlling switch 8. The magnetic element may be mounted above the table in any suitable manner, but for the purpose of illustration, I have shown the same as supported upon arched brackets 9 which are secured to said element and bolted to the table 1 to rigidly mount the element 5 in position.

40 This invention contemplates relative movement between the supporting bed 2 and the magnetic element 5, so that they may be moved toward and away from one another to bring the face of one substantially into engagement with the face of the other at the will of the operator. In practice, the bed may be stationary and the magnetic element movable, but for the purpose of illustration, I have chosen to show the magnetic element stationary and the bed movable. To permit of this, the supporting bed 2 is provided with a depending stem or post 10 which is rigid with the bed and extends downwardly through a guide in the table 1 so as to guide the bed for up and down movement. With the lower end of this post 10 or plunger 10 is associated appropriate means for raising and lowering the bed. This means may partake of various forms without departing from this invention, but, for the purpose of illustration, I have shown the post 10 as pivoted to a lever 11 pivotally mounted on a hanger 12 by means of a pivot 13 and the forward end of said lever is connected by a link 14 to a treadle 15 projecting into convenient position to be actuated by the foot of the operator. The weight of the bed is such as to normally cause it to be seated on top of the table 1, but when desired the operator may apply foot pressure to the treadle 15 for the purpose of lifting the bed.

75 The normal position is the lowered position shown in Figure 1. In carrying out this inven-

tion, I may use a conventional mounting board 16, a corner fragment of which is shown in Figure 2. This board is conventional and is of the type that has long been used in the industry. It may be made of wood or metal, but is shown as made of wood slab 16, the upper face of which is recessed or depressed at 17 and the said recess is divided by means of partitions 18 into a series of pockets adapted to hold tiles in closely spaced apart relation. I make no claim to this board for it is conventional and therein lies one of the important factors of the present invention because through this invention, I am able to use the old and well known board and do not require special boards for the purpose.

90 In carrying out this invention, I employ appropriate filler pieces which may vary in size and shape according to requirements. Three of these filler pieces are shown in Figures 3, 4 and 5. The material employed must be, in part, material which will respond to magnetism and in part of material which will not respond to magnetism. I find it desirable, although not necessary, to make the fillers of laminated form. For instance, the base part 19 of the filler 20 in Figure 3 is di-magnetic, preferably of aluminum, while the face 21 is of soft iron. The reason for this is that the partitions 18 of the mounting board are generally of steel and it is essential that there be no actual contact between the magnetized part 21 of the filler piece and these partitions. If the magnetic part 21 touches an iron or steel part of the board the fillers and board become one when the fillers are magnetized, as hereinafter more fully described. If the mounting board is wholly di-magnetic then wholly magnetic fillers may be used.

100 I wish it understood, however, that the present invention is not limited to the laminated arrangement shown, but that the filler pieces may be wholly or partly magnetically responsive within the purview of this invention. The filler piece 20 of Figure 3 is shown as square, while the filler piece 20 of Figure 4 is hexagonal. These filler pieces may be of any appropriate shape and of 105 a size to fit into compartment of the mounting board 16, or for setting up certain patterns such as basket weave or the like, the filler pieces may be made larger than one compartment and may be slotted at 22 as indicated, for example, in Figure 5, so as to straddle the partitions as may be desired.

110 I do not wish to limit the invention to the shape or sizes of these filler pieces as they may be varied within wide limits depending upon the 115 desire required.

120 In carrying out this invention with the apparatus as described, I proceed as follows. Having determined upon the pattern to be produced, which we will assume, for the purpose of illustration, is a checker board pattern of blue with one inch square tiles, the operator takes the conventional mounting board and drops into every alternate space in said board, a filler piece which may be square, round, hexagonal or of any other 125 suitable shape with the magnetically responsive side of the filler piece up in the event that the filler pieces are constructed of laminated form. If they are all metal, either side of the filler pieces may be up. Having assembled, in the 130 manner described, the filler pieces in every alternate space of the board, which we will assume corresponds to the spaces for blue tiles, the operator deposits on the board in the same manner as under prior practice a quantity of white tiles 135

and by shaking the board in the conventional way deposits white tiles in the spaces not occupied by the fillers. Excess tiles are then scraped off and the board is then picked up and placed on the bed 2 with two of its edges in engagement with the stops 3 and 4, as shown in Figure 6. The operator thereupon applies pressure to the foot treadle to raise the bed and bring the board into face abutting relation with the electro-magnetic elements 5, as shown in Figure 7. This having been done and while the board is held in this position momentarily the switch 8 is closed to turn on the current and energize the electromagnet. The switch is left on and pressure on the treadle is released allowing the bed to descend. As it descends the fillers will be left magnetically attached to the electromagnet, as shown in Figure 8, and the spaces occupied by the fillers in the board will be vacant. The board is now removed from the bed and blue tiles are shaken over the board and fill the spaces intended for the blue tiles in the design. The board is next passed to another operator who adhesively applies the paper backing in the conventional way. The next board without tiles or fillers therein is thereupon placed on the bed 2, as shown in Figure 9, with two of its edges in contact with the stops 3 and 4. The treadle is operated and the bed is elevated to bring the board in facial engagement with the electromagnet. While held in this position, the switch 8 is opened to deenergize the electromagnet and the fillers immediately are released into the spaces appropriate to the blue tiles in the same relation as in the previous board. The bed is dropped, as shown in Figure 10, the board is removed and tiles are shaken into the vacant spaces, whereupon the operations described are repeated.

It will be noted, therefore, that it is only necessary to set up the first board in order to get the proper pattern after which the pattern is duplicated automatically in the manner described. The most complex patterns can be set up in the manner described and reproduced as stated with a single set up.

It will of course be apparent to those skilled in this art that a number of boards may be initially set up so that a number of operatives may be employed at the same time at different stages of the process without any particular operator holding up another.

I also find that if desirable I may use dummy boards, i. e., boards with recesses or pockets only at those points where filler pieces will be desired for any particular design and in this way, I dispense with the manual set up at any time. In other words, such a dummy board for a two-color checker board design would consist in a board the size of a mounting board but having in its upper face alternating pockets with the intervening spaces filled in or blank. With such a board, it would only be necessary to shake filler pieces over the surface thereof and they will automatically fall into place. Then set such board on the bed, raise it into contact with the electromagnet, energize the magnet to remove the fillers and drop the board. The board may then be laid aside for the next set up and successive conventional boards may be used with a set of filler pieces set up as stated.

It will of course be understood that with slight modifications of filler pieces, a wide variety of designs may be produced among the most common of which are, herringbone, basket weave, checker patterns, square or polygonal patterns

with lines or blocks of two color in an almost infinite number.

An important practical factor of the present invention is that it materially speeds up production and what is more important, it produces absolute uniformity in designs and eliminates mistake due to the human element in manual set ups for it will be apparent that if the original set up is correct every succeeding set up must be absolutely the same. Furthermore, it has heretofore been the practice in making an original set up to place in each board tiles of one color, so that they fill all of the spaces and thereupon operators laboriously pick out from the filled board the tiles from the spaces which should contain the other color. This operation must be accurately accomplished and is particularly injurious to the finger tips of the operator as the edges of the tiles are frequently sharp and abrasive in character. The work must be done slowly and with the utmost care. All of this is wholly eliminated by the present invention and the operator may work without injury to the hands at any time. If desired, the flow of current to the electromagnet may be controlled from the treadle so that the machine may be automatic and does not require the separate operation of turning on the current manually and independently of operation of the treadle.

I have particularly referred to the invention as adapted for the mounting of designs of different colors, but it will be understood that the invention may be carried out to mount tiles of different shapes or of different sizes and of the same or different colors.

The foregoing detailed description sets forth the invention in its preferred practical form, but the invention is to be understood as fully commensurate with the appended claims.

Having thus fully described the invention, what I claim as new and desire to secure by Letters Patent is:

1. In an apparatus for facilitating the mounting of tiles, the combination of a board supporting bed and an electromagnetic element mounted for relative movement to permit a mounting board supported on said bed and having therein tile pockets to be brought into or out of substantially facial engagement with respect to the electromagnetic element, means for producing such relative movement, electromagnetically responsive filler elements adapted to be positioned within predetermined pockets of the board and adapted to be positioned through such relative movement in and out of magnetic relation to the electromagnetic element, and current switching means for energizing and de-energizing said electromagnetic element as and when desired.

2. In an apparatus for facilitating the mounting of tiles, an electromagnetic element mounted in substantially horizontal position, a bed juxtaposed with said element and mounted for movement toward and away from the same, a mounting board provided therein with pockets, magnetically responsive fillers removably positioned in predetermined pockets in accordance with the pre-arranged design, means for centralizing said board upon said bed, means for actuating the bed to lift the same to bring said fillers into proximity with the electromagnetic element, an electric circuit including a switch for energizing said electromagnetic means when desired, whereby the magnetic means may be energized to grip and hold the fillers while the board is lowered with the table and removed therefrom, and may also

be de-energized to release the fillers into the pockets of the board when said board or a similar one is elevated with the table to position the corresponding pockets to receive said fillers.

- 5 3. In apparatus of the character described, electromagnetic means, means for supporting a mounting board with pockets for movement toward and away from the electromagnetic means, magnetically responsive filler members adapted to occupy pockets of said board, means for moving said board into and out of cooperative relation with the electromagnetic means, and means for energizing and de-energizing said electromagnetic means.
- 10 4. In an apparatus for facilitating the mounting of tiles, the combination of a mounting board support, means for facilitating the positioning of successive mounting boards upon said board in identical relation thereto, electromagnetic means,

means for effecting relative movement between said support and electromagnetic means to bring them into and out of relatively close facial proximity, means for energizing and de-energizing said electromagnetic means when desired, whereby magnetically responsive elements may be removed from or replaced in the tile pockets of mounting boards positioned in succession upon said support.

80 5. A filler member for use in tile mounting apparatus, comprising a base portion of non-magnetic material and a facial portion of magnetic material.

85 6. A filler member for use in tile mounting apparatus, comprising a magnetic portion and a diamagnetic portion, said portions being secured together to be handled as a unit.
